UNITED STATES PATENT OFFICE.

GEORGE W. GAGE, SR., OF EPPING, NEW HAMPSHIRE.

FOOT-REST FOR RADIATORS.

No. 911,488.

Specification of Letters Patent.

Patented Feb. 2, 1909.

Application filed April 22, 1908. Serial No. 428,561.

To all whom it may concern:

Be it known that I, GEORGE W. GAGE, Sr., a citizen of the United States, residing at Epping, in the county of Rockingham and 5 State of New Hampshire, have invented certain new and useful Improvements in Foot-Rests for Radiators, of which the following is a specification, reference being had to the accompanying drawings.

10 My invention relates to improvements in foot rests for radiators and the like.

The object of the invention is to provide a device of this character which is simple and practical in construction, durable in use and 15 easy to apply to and remove from radiators of different sizes.

With the above and other objects in view, the invention consists of the novel features of construction and the combination and arrangement of parts hereinafter fully described 20 and claimed, and illustrated in the accompanying drawings, in which—

Figure 1 is a side elevation of a radiator showing my improved foot rest applied thereto; Fig. 2 is a plan view, parts being in section; and Figs. 3 and 4 are detail longitudinal and transverse sections taken, respectively, on the planes indicated by the lines 3—3 and 4—4 in Fig. 2.

30 In the drawings 1 denotes a steam or hot water radiator of well known form and construction to which my improved foot rest is detachably secured.

The invention comprises a body 2 which is 35 preferably, but not necessarily, made extensible to adapt it to radiators of different lengths within a certain limit. As illustrated, the body is composed of two similar members each having a head 3 carrying a 40 leg piece 4 and rods 5, the rods of the two members being slidably or telescopically engaged. The rods 5, of which any number may be provided, are preferably made tubular so that those on one end member or head 45 will slide within those on the other and in order to prevent said rods from being pulled entirely apart I may provide upon the ends of the smaller ones stop collars 6 and upon the ends of the larger ones stop collars or 50 caps 7. The latter are removable, being secured in position by set screws 8. By constructing the rods in this manner it will be seen that the two parts or members of the device may be readily disconnected. The 55 leg pieces or members 4 are hinged to the end members or heads 3 by pivot rods 9 to which

they are rigidly secured so that they can swing from a horizontal position, shown in dotted lines in Fig. 1, to a vertical position shown in full lines in said figure. When in such 60 vertical position they engage stop lugs or projections 10 depending from the end members or heads 3 and are retained in such position against said stops by set screws 11 or equivalent means. The rear ends of the 65 pivots 9 are extended so that they may be projected between two adjacent loops or sections of the radiator 1 and upon their extremities are cross bars 12 or equivalent 70 means to engage the rear faces of the radiator sections to secure the device to the radiator. The cross bars or arms 12 are disposed in planes at right angles to the planes of the leg pieces 4 so that when the latter are vertical said cross pieces will be disposed horizontal to prevent the device from being moved away from the radiator, and when said leg pieces are horizontal the cross bars will be 75 vertical to permit of the ready removal of the device from the radiator or its attachment thereto, as will be readily understood upon reference to Fig. 1.

By pivoting the leg pieces to the body and providing their pivots with laterally projecting arms or cross bars it will be seen that 80 the device may be quickly and easily applied to and removed from a radiator and that by making it of two slidably or telescopically engaged members it may be adjusted in 85 length to accommodate different size radiators.

The rods 5 are so disposed as to support the feet at a convenient distance from the radiator, and in order to strengthen the central portion of the body, especially when its 90 two members are extended, I may provide an intermediate leg piece 13 which is suitably secured to the larger of the two sets of tubes or rods 5. This intermediate leg piece is not provided with the radiator attaching means 100 as are the two end or outer leg pieces.

Having thus described my invention what I claim is:

1. A foot rest for radiators comprising a body, pivots partially movable therein, leg 105 pieces fixed to said pivots and movable therewith, and means fixed to said pivots and movable therewith for engaging the sections or pipes of a radiator to secure the device thereto.

2. A foot rest for radiators comprising a body, transversely arranged pivots per-

- tially rotatable in the body adjacent its ends, leg pieces fixed to the outer ends of said pivots and movable therewith and arms fixed to the inner ends of said pivots and 5 movable therewith, said arms being adapted to engage the pipes or sections of a radiator to secure the device thereto.
3. A foot rest for radiators comprising a body, pivots arranged transversely upon the 10 body and partially rotatable therein, leg pieces carried by the outer ends of the pivots and movable therewith, means carried by the inner ends of the pivots and movable therewith, said means being adapted to engage 15 the sections or pipes of a radiator to secure the device thereto and means for holding said leg pieces against movement.
4. A foot rest for radiators comprising a body, pivots arranged transversely upon the 20 body and partially rotatable therein, leg pieces carried by the outer ends of the pivots and movable therewith, means carried by the inner ends of the pivots and movable therewith, said means being adapted to engage 25 the sections or pipes of a radiator to secure the device thereto, stops for limiting the swinging movement of the leg pieces and means for retaining the leg pieces in engagement with said stops.
- 30 5. A foot rest for radiators comprising a body, transverse pivots partially rotatable therein, leg pieces fixed to the outer ends of said pivots and movable therewith, laterally projecting arms fixed to the inner ends of the pivots and adapted to enter between and engage the sections or pipes of a radiator to secure the device thereto, stop projections upon the body to limit the movement of the leg pieces and set screws for 35 retaining the leg pieces in engagement with said stop projections.
6. A foot rest for radiators comprising a body, longitudinally and vertically swinging leg pieces upon the body and adapted to 40 engage the floor and means to engage the pipes or sections of a radiator disposed in planes substantially at right angles to the planes of the leg pieces, said radiator engaging means being operatively connected to the leg pieces for simultaneous movement therewith, substantially as and for the purpose set forth.
7. A foot rest for radiators comprising a body, leg pieces hinged to the body for swinging movement in the direction of its length and adapted to engage the floor to support 45 the body, arms to engage the sections or pipes of a radiator disposed in planes substantially at right angles to the planes of the 50 foot pieces and fixedly connected to said foot pieces for simultaneous movement therewith.
8. A foot rest for radiators comprising a body having an intermediate member, end members, and longitudinally extending rods 55 projecting inwardly from the end members and slidably engaged with each other whereby the body may be varied in length, the intermediate member being carried by the inner ends of the rods upon one of the end members, and leg pieces hinged to said end members and carrying means to engage the sections or pipes of a radiator to secure the device thereto.
9. A foot rest for radiators comprising a body longitudinally extensible whereby it 70 may be varied in length, leg pieces hinged to the ends of said body, and means connected to the leg pieces and movable therewith for engaging the sections or pipes of a radiator to secure the device thereto.
10. A foot rest for radiators comprising a body, leg pieces hinged to the ends of said body, and means connected to the leg pieces and movable therewith for engaging the sections or pipes of a radiator to secure the 75 device thereto.
11. A foot rest for radiators comprising a body, leg pieces hinged to the ends of said body, means connected to the leg pieces and movable therewith for engaging the sections or pipes of a radiator to secure the device thereto, and means for holding said leg pieces against movement.
12. A foot rest for radiators comprising a body, leg pieces hinged to the ends of said body, means connected to the leg pieces and movable therewith for engaging the sections or pipes of a radiator to secure the device thereto, stops for limiting the swinging movement of the leg pieces and set screws 90 for holding said leg pieces against said stops.
13. A foot rest for radiators comprising a body extensible in length to correspond to the length of the radiator to which it is applied and means for attaching the device to a 105 radiator.
14. A foot rest for radiators comprising a longitudinally extensible body having an intermediate member, end members and longitudinally extending rods projecting from said 110 end members and slidably engaged with each other whereby the body may be varied in length, the intermediate member being carried by the inner ends of the rods upon one of the end members.
15. A foot rest for radiators comprising a longitudinally extensible body having end members and telescopically engaged rods projecting from said end members and provided with stops to limit their movement on 115 each other and means for fastening the device to a radiator.
16. A foot rest for radiators comprising a body, rotary pivot rods in said body, leg pieces fixed to the outer ends of the pivot 120 rods and adapted to engage the floor to support the body, and right angularly projecting arms upon the inner ends of said pivot rods disposed in planes at right angles to the planes of said leg pieces and adapted to enter be- 125

tween the coils of a radiator when the leg pieces are turned to a horizontal position and to pass in rear of said coils and lock the device to the radiator when the leg pieces are 5 swung to a vertical position and engaged with the floor.

17. A foot rest for radiators comprising a body, rotary pivot rods in said body, leg pieces fixed to the outer ends of the pivot 10 rods and adapted to engage the floor to support the body, right angularly projecting arms upon the inner ends of said pivot rods disposed in planes at right angles to the planes of said leg pieces and adapted to enter 15 between the coils of a radiator when the leg pieces are turned to a horizontal position and to pass in rear of said coils and lock the device to the radiator when the leg pieces are swung to a vertical position and engaged 20 with the floor, and means for holding the leg pieces against movement.

18. A foot rest for radiators comprising a longitudinally extensible body, rotary pivot rods in said body, leg pieces fixed to the outer ends of the pivot rods and adapted to 25 engage the floor to support the body, right angularly projecting arms upon the inner ends of said pivot rods disposed in planes at right angles to the planes of said leg pieces and adapted to enter between the coils of a 30 radiator when the leg pieces are turned to a horizontal position and to pass in rear of said coils and lock the device to the radiator when the leg pieces are swung to a vertical position and engaged with the floor, and means for 35 holding the leg pieces against movement.

In testimony whereof I hereunto affix my signature in the presence of two witnesses.
